UNITED STATES PATENT OFFICE.

WILLIAM E. FOWLER, SR., OF CHICAGO, ILLINOIS, ASSIGNOR TO THE FOWLER CAR COMPANY, OF CHICAGO, ILLINOIS, A CORPORATION OF ILLINOIS.

DUMP-CAR.

1,169,790.

Specification of Letters Patent.

Patented Feb. 1, 1916.

Application filed August 5, 1915. Serial No. 43,722.

To all whom it may concern:

Be it known that I, WILLIAM E. FOWLER, Sr., a citizen of the United States, and resident of Chicago, in the county of Cook and State of Illinois, have invented certain new and useful Improvements in Dump-Cars, of which the following is a specification.

My invention relates to railway cars and has particular reference to a novel dump car so arranged as to permit the discharge of the entire load to either side of the car.

It is desirable in the handling of coal, sand, gravel, and other granular material to provide means for dumping the contents of a car. Preferably such means should provide for dumping the entire load, and while this is not uncommon, I believe it to be new to provide means for dumping the entire load to either side of the car utilizing the weight of the material itself for effecting the movement of the dumping doors.

The invention will be more readily understood by reference to the accompanying drawings wherein—

Figure 1 is an end elevation of a gondola car to which my invention has been applied; Fig. 2 is a transverse section through the car showing the doors in normal position; Fig. 3 is a view similar to Fig. 2, showing the first step in the dumping action; Fig. 4 is a similar view showing the completed dumping movement; and Fig. 5 is a section on the line 5—5 of Fig. 2.

Referring more particularly to the drawings it will be seen that the car includes center sills 10 on which are mounted needle beams 11 serving to support the side walls 12 of the car. The floor of the car is composed substantially wholly of doors 13 which extend from side to side of the car and are provided with a central pivot 14 which operates in a slot 15 in a bracket 16 which is mounted on center sill cover plate 17. The ends of the doors may be normally supported by rack bars 18 movable in a horizontal plane beneath the doors by means of a pinion 19 mounted on a shaft 20 extending to the end of the car and to which a crank 21 may be fitted. It will be seen that the doors are normally held in a position in which the pivot 14 occupies the upper portion of the slot 15. At each side of the pivot and secured to the doors are brackets

22 having slots 23 therein. Pins 24 are seated in the slots 23, the pins being rigidly secured to a vertically-movable rack 25 slideable in a fixed path in a housing or bearing 26 which is secured to the center sills. A pinion 27 engages the rack bar, all of the pinions in a line being mounted on a shaft 28 which extends to the end of the car and carries a star wheel 29.

It will be understood in the operation of the device that one rack bar is intended to move upwardly while the other moves downwardly. I have therefore provided means for securing this action, a simple exemplification of which means is shown in Fig. 1 and comprises a hand lever 30 and links 31, 32 the link 32 being rotatable on the shaft 70 29 and carrying a pawl 33 which may engage either side of the star wheels 29. While adjusting the pawls it will be seen that the shafts may be moved in the same or opposite directions, as desired.

The operation is as follows: Assuming the car to be loaded with granular material and that it is desired to dump the same to the left, as viewed in the figures, the left hand outer shaft 20 is rotated to withdraw 80 the rack bar 18 from beneath the door. The right hand central shaft being held against rotation, and the left hand central shaft being free to revolve, it will be seen that the doors will have a tendency to rotate 85 about the right hand pin 24 and this rotation will be positive because of the superposed load on the door to the left of such pivot. The doors will then drop to the position of Fig. 3; that is, to the point where 90 the door pivots 14 occupy the lower portion of the slots 15. The load having started to discharge, the preponderance will be to the left of the pivot, and upon releasing the right hand central shaft the door will continue to tilt until it reaches the position of Fig. 4. If this should not occur, the movement of the door may be made positive by actuating the handle 30 and arranging the pawls in such manner that one rack bar is 100 moved upward and the other downward. If it be desired to dump the load on the opposite side, the same steps will be taken with the opposite parts.

Obviously the instrumentalities for effecting this result may be changed in many par-

ticulars and I do not, therefore, wish to be limited to the construction shown and described.

I claim:

5. 1. In a dump car, the combination of car walls and a door extending substantially entirely across the width of the car, a floating pivot for the door, said pivot being located at substantially the center of the car, and means located at each side of the center of the door a portion of which means is adapted to act as a pivot for the door upon the releasing of one edge thereof, substantially as described.
10. 2. In a railway car, the combination of side walls and a floor, said floor being composed of a series of single doors which extend from side to side of the car, a vertically shiftable pivot for each of said doors, the pivot being located at substantially the transverse center of the door, supporting means for the edges of the doors, and vertically movable pivots located at each side of the center of each door, substantially as described.
15. 3. In a railway car, the combination of a center sill, side walls and floor, said floor being composed of a series of single doors extending from side to side of the car and provided with a transversely-centralized pivot, said pivot being mounted in a vertically-elongated bearing, and vertically-movable stops mounted at each side of the door and adapted for vertical reciprocation in opposite directions whereby said doors may be tilted and the load discharged to either side of the car, substantially as described.
20. 4. In a railway car, the combination of side walls and a floor, said floor being composed of a series of single doors extending from side to side of the car, means at the outer edges of the doors for normally maintaining the doors in position, a central pivot for each door, and vertical reciprocable rack bars and pinions mounted at each side of the center of each door, a shaft for actuating each rack bar, and means for actuating said
25. shafts whereby to simultaneously move said rack bars in opposite directions, substantially as described.
5. In a railway car, the combination of side walls and a floor, said floor being composed of series of doors which extend from side to side of the car and each door being provided with a central, shifting pivot, vertically-reciprocable members located at each side of the pivot, means for actuating said members and for releasing one or both thereof as required, the parts being arranged whereby one of said members may be released and the door be permitted to pivot on the other member through distances determined by said shiftable pivot, substantially as described.
6. In a dump car, the combination of side walls and a floor, the floor being composed of a series of single doors which extend from side to side of the car, vertically shiftable supporting devices for said doors, one of said devices being located on each side of the longitudinal center of the car, said doors being pivoted on said supporting devices, whereby when one of said supporting devices is lowered, the door will pivot upon the other of said supporting devices, substantially as described.
7. In a dump car, the combination of side walls and a floor, the floor being composed of a series of single doors which extend from side to side of the car, vertically shiftable supporting devices for said doors, one of said devices being located on each side of the longitudinal center of the car, said doors being pivoted on said supporting devices, whereby when one of said supporting devices is lowered, the door will pivot upon the other of said supporting devices, and means located at the outer edges of the door for rigidly supporting the door when in closed position, substantially as described.
